Company, East Pittsburgh, Pa., a corporation of
Pennsylvania

Application March 27, 1937, Serial No. 133,419

13 Claims. (Cl. 80—35)

My invention relates, generally, to tension control systems and, more particularly, to fluid-pressure operated tensiometers for automatically maintaining a predetermined tension on material which is passing through the roll stands of a tandem rolling mill.

Numerous methods have been proposed for maintaining a predetermined constant tension on the material passing between the roll stands of a tandem mill. One prior method is to subject the material to a tension by means of an idler roller mechanism disposed to apply a force transverse to the path of movement of the material which varies in accordance with the degree of deflection of the material between predetermined limits of movement. Compensation for variation in the degree of deflection of the material from its normal path of travel is provided by mounting the idler roller on a bell crank device having an angle between its arms which causes the tensioning device to be self-compensating over a certain range of operation and permits a limited amount of movement of the idler roller resulting from variations in the length of material between roll stands without appreciably changing the tension on the material. The tension producing force is provided by mounting an adjustable weight on the horizontal arm of the bell crank lever, thereby causing the idler roller, which is carried by the other arm, to exert a predetermined force against the strip of material. However, devices of this type have been found to be relatively slow in action because of the inertia of the heavy weight required to produce the necessary force. Furthermore, it is difficult to adjust the weight while the device is in operation and, therefore, impracticable to vary the pressure on the material to control the tension while a strip is passing through the rolls.

Accordingly, an object of my invention is to provide a tensiometer for maintaining a tension on a strip of translatory material which will respond quickly to changes in the length of the material between the roll stands of a rolling mill.

Another object of my invention is to provide a tensiometer which may be readily adjusted to vary the tension on a strip of material while it is passing through the roll stands.

A further object of my invention is to provide for regulating the pressure exerted by a tensiometer in a tension control system.

A more general object of my invention is to provide a tension control system which will be

simple and efficient in operation and which may be economically constructed and installed.

Other objects of my invention will be described fully hereinafter or will be apparent to those skilled in the art.

In accordance with one embodiment of my invention, which may be applied to a rolling mill where it is desired to control the tension on the material between any two roll stands, the material is subjected to a transverse force at a point 10 between the roll stands by means of an idler roller which is mounted on one end of a bell crank lever having an angle between its arms which causes the tensioning device to be self-compensating over a certain range of operation. 15 The other end of the lever arm is attached to a fluid-pressure operated piston which raises the idler roller against the strip of material. The pressure in the cylinder housing the piston is regulated and kept constant by a fluid pressure 20 regulating valve of the spring-loaded diaphragm type. The pressure maintained by the valve can be varied by an electrically energized solenoid disposed to counteract the spring in the regulating valve. The current in the solenoid 25 may be controlled manually by means of a rheostat, or automatically by means of a vibrating or other suitable regulator.

For a fuller understanding of the nature and objects of my invention, reference may be had 30 to the following detailed description, taken in conjunction with the accompanying drawing, in which the single figure is a diagrammatic view of a tension control system embodying my invention.

Referring now to the drawing, the control system shown comprises a pair of roll stands 10 and 11 through which a strip of material 12, such as sheet steel, is passed. The roll stands 10 and 11 may be driven in any suitable manner, 40 as by means of motors 13 and 14, respectively, which are connected to their respective roll members through gear sets 15 and 16.

The roll motors 13 and 14 are provided with armature windings 17 and 18 and separately excited fields windings 19 and 20 respectively. The armature windings may be energized from any suitable source of direct current power (not shown) through conductors 21 and 22, the motors 13 and 14 being connected thereto by controllers 23 and 24, respectively. The separately excited field windings 19 and 20 are energized from power conductors 25 and 26, as will be explained more fully hereinafter.

In order to provide for maintaining a prede- 55

terminated tension on the material 12, there is utilized a tensioning device for exerting a transverse deflecting force on the material between the roll stands 10 and 11. If a deflecting force 5 is applied to the material 12 midway between the two stands, so as to move it from the plane of the straight pass line extending between the roll stands to a deflected position, the tension on the material will be a function of the sine of 10 the angle of deflection alpha and the tension will remain substantially constant so long as the strip is maintained in this position under a constant force.

However, if the length of the material between 15 the roll stands increases and the same constant deflecting force is applied, the angle of deflection becomes greater and, therefore, the tension on the material is reduced. The opposite is true 20 in the event that the length of the material between the roll stands decreases, thereby causing the tension on the material to increase.

In view of the foregoing, it will be understood 25 that in order to maintain a predetermined tension on the material, provision must be made for not only maintaining the tensioning means, which applies the force to the material, as nearly as possible in a certain position, but provision must also be made for causing a variation to occur in the amount of force produced by the 30 tensioning means, depending upon the degree of deflection of the material from its normal path of travel. In general, the pressure characteristic must be such that the pressure increases with increasing height of the material above the pass 35 line.

In the present invention, this result is accomplished by utilizing a tensioning device which comprises an idler roller 31 mounted on one end of a bell crank lever 32 and a fluid pressure operated piston 33 which is disposed in a cylinder 34 and so connected to the other end of the bell 40 crank lever 32 that the roller 31 is forced against the material 12. The bell crank lever 32 is pivotally mounted at 35 in order that the piston 33 may be utilized to force the roller 31 upwardly against the material.

In order to maintain a predetermined tension on the material, the pressure in the cylinder 34 is regulated by means of a regulating valve 36, 50 which is utilized to so vary the pressure ratio from inlet to outlet that, with a constant inlet pressure, a varying outlet pressure may be obtained. The outlet of the regulating valve 36 is connected to the cylinder 34 by means of a pipe 37 and the inlet of the valve may be connected to an air pressure tank 38, as shown. If desired, other suitable working mediums, such as any other gas or liquid, may be utilized in place of air.

60 The regulating valve 36 comprises a body 41 provided with an inlet opening 42 and an outlet opening 43, which may be connected respectively to the supply reservoir 38 and the line 37 leading to the fluid-pressure operated piston 33. The body 41 is provided with a spring cover 44 that houses a compression spring 45, the compression of which may be varied by means of a plunger 46. As shown, the spring 45 is disposed to control the position of a diaphragm 47 which, in 65 turn, controls the operation of a valve 48.

In the present structure, the spring 45 is so constructed that the maximum pressure applied to the diaphragm 47 is sufficient to provide the maximum pressure required in the cylinder 34 70 and the plunger 46 is disposed to counteract the

pressure of the spring 45. Air is admitted through the inlet opening 42, past the valve 48 until the pressure within the body 41, which is applied to the diaphragm 47, is sufficient to overcome the compressive force of the spring 45. The diaphragm 47 is then moved downwardly sufficiently to permit a spring 49 to close the valve 48, thereby preventing the further flow of air through the inlet opening 42.

When the pressure within the body decreases 10 to a value which is insufficient to maintain the diaphragm 47 in a position to permit the valve 48 to remain closed, the valve is opened slightly to permit air to flow through the inlet opening 15 to increase the pressure in the body of the valve and in the cylinder 34. Thus, it will be seen that the outlet pressure may be regulated by varying the compression of the spring 45. If the spring pressure on the diaphragm 47 is increased, the outlet pressure increases and vice versa.

20 In order to provide for readily adjusting the valve 36 to vary the pressure maintained in the cylinder 34, an electrically energized solenoid 51 is connected to the plunger 46. The solenoid 51 may be energized from the power conductors 25 and 26, or from any other suitable source, and the current flowing through the coil of the solenoid may be controlled by means of a manually operated rheostat 52 or by means of a regulator of the vibrating or other suitable type. In this 30 manner, the operator can readily change the pressure in the cylinder 34, thereby controlling the tension on the material 12 to maintain a constant gauge of material or in case it is desired to change the gauge, this may be accomplished within certain limits by increasing or decreasing the tension, as the case may be.

In order that the tensioning device may inherently function to maintain the tension substantially constant over a certain range of operation or deflection of the material 12, the arm 32, which carries the roller 31, should be positioned at an angle of approximately 51° from the plane through the pivot 35 parallel to the normal pass line of the material. This arrangement or design 45 causes the tensioning device to be self compensating over a maximum range of operation and permits a limited amount of movement of the roller 31 resulting from variations in the length of the material between the roll stands without appreciably changing the tension on the material 50 so long as the pressure provided on the bell crank lever by the piston 33 is substantially constant. The transverse or deflecting force exerted upon the material by the roller 25 is thereby automatically varied in accordance with the position of the roller in such manner as to maintain the material under substantially constant tension.

It is apparent that when the roller 31 moves upwardly, which requires a greater vertical or transverse force in order to maintain the tension substantially constant, the distance between the vertical planes extending between the pivot point 35 and the center of the roller 31 is decreased, 65 which causes an increase in the deflecting force. Likewise, when the roller 31 is depressed to a position below normal, the distance between these same two points is increased, which correspondingly reduces the deflecting force in such proportion as to maintain a substantially constant tension.

70 While the tensioning device herein described will satisfactorily maintain the tension over a wide operating range, it is desirable to make pro- 75

vision for constantly maintaining the tensioning device in as near a predetermined operating position as possible. This may be accomplished by controlling the speed of at least one of the roll stand motors in accordance with the vertical movements of the tension roller 31 in such a manner that should the deflection of the material vary from a value considered as normal, the speed of at least one of the motors is varied in order to take up the excess length in the strip of material or to increase its length, as the case may be.

As shown, provision is made for automatically controlling the speed of the motor 13 by means of a regulator device 54, the functioning of which is caused to be influenced in accordance with the position of the roller 31. As stated hereinbefore, the separately excited field windings 19 and 20 of the motors 13 and 14, respectively, are energized from the power conductors 25 and 26. The field circuit of the motor 14 is provided with a variable resistance 55, which may be utilized to adjust the speed of the roll stand 11. Likewise, the motor 13 is provided with a field rheostat 56 which may be utilized to adjust the speed of the roll stand 10. In addition to the rheostat 56, the field circuit of the motor 13 contains resistors 57 and 58 which are controlled by shunting switches 59 and 61, respectively, which are, in turn, controlled by the regulator 54.

While the regulator 54 has been illustrated as a vibrating type, it will be understood that a regulator of any suitable type may be utilized. The vibrating contact element 62 is operated in a well known manner by means of an electromagnet 63 and an auxiliary relay 64. When the power conductors 25 and 26 are energized, the electromagnet 63 is energized and raises the contact element 62 to its uppermost position. The energizing circuit for the electromagnet 63 contains a resistor 65 which is shunted by the auxiliary relay 64. Upon the operation of the electromagnet 63, its contact members 66 are closed to energize the auxiliary relay 64 which opens its contact members to insert the resistor 65 in the circuit for the electromagnet 63. This increases the resistance of the circuit for the electromagnet 63 to such an extent that the vibrating contact element 62 is returned to its lowermost position. This cycle of operation is repeated thereby causing the contact element 62 to vibrate.

The regulator 54 is provided with an adjustable contact element 67 having upper and lower contacts which are positioned in any suitable manner in accordance with the position of the roller 31. As shown, the contact element 67 is directly connected to the bell crank lever 32 by an arm 68 to transmit the motion of the roller 31 to the contact element 67.

In order to more clearly describe the functioning of the regulator 54 to control the speed of the motor 13 in accordance with the movements of the roller 31, it will be assumed that the material 12 is traveling in the direction indicated by the arrow. Under this condition, the speed of the motor 13 must be increased when the deflection increases and decreased when the deflection decreases.

When the vibrating contact element 62 is in its lower position, it engages the lower contact of the adjustable contact element 67 and the shunting relay 61 is energized to remove a shunt connection from the field resistor 58, thereby decreasing the excitation of the motor 13 and increasing its speed accordingly. When the contact element 62 is in its upper position, the shunt-

ing relay 59 is energized to shunt the resistor 57 from a field circuit thereby increasing the excitation of the motor which causes its speed to decrease.

The regulator 54 is so disposed that when the tension roller 31 is in its normal operating position, the vibrating contact element 62 makes contact with the upper and lower contacts of the adjustable contact element 67 for equal periods of time. If, however, the deflection in the material 12 increases, the adjustable contact element 67 of the regulator 54 is so positioned that the vibrating element 62 engages the lower contact of the contact element 67 for a greater time than it engages the upper contact, thereby causing the shunting switch 61 to be maintained in its open position over longer periods of time than the shunting switch 59, which causes the speed of the motor 13 to increase a sufficient amount to reduce the deflection of the material 12 to normal.

The opposite is true when the deflection decreases below its normal value, thereby causing the shunting switch 59 to be maintained energized over longer periods of time than the switch 61. In this manner, the speed of the motor is decreased and the deflection of the material 12 increased.

In order to provide for controlling the position of the roller 31 when it is not in engagement with a sheet of material, a hydraulic device 71 may be utilized to function as a stop for the lever arm 32. The device 71 comprises a piston 72 disposed in a cylinder 73 which also contains a spring 74 disposed to raise the piston 72 to lower the roller 31 when it is desired to start a new sheet of material through the roll stands 10 and 11. The piston 72 may be lowered by a pressure fluid under the control of valves 75 and 76 while the tensioning device is in operation.

From the foregoing description, it is apparent that I have provided a tensioning device which, on account of its facility for readily changing the applied pressure, permits the operator to control not only the tension but also the gauge of the material very closely. Thus, if the gauge of the material should decrease, the operator may readily decrease the pressure, thereby causing the gauge to increase, or if the gauge increases, the operator can increase the pressure, and thereby by the tension on the material, to maintain the desired gauge.

Since numerous changes may be made in the above described construction and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In a tension control system, in combination, a movable tensioning roller, fluid-pressure operated means for actuating said roller, means for regulating the amount of fluid pressure on said fluid-pressure operated means, and electrically energized means for governing the operation of said regulating means to control the operation of the tensioning roller.

2. In a tension control system, in combination, a movable tensioning roller, fluid-pressure operated means for actuating said roller, means for regulating the amount of fluid pressure on said fluid-pressure operated means, electrically energized means for governing the operation of said regulating means to control the operation of the tensioning roller.

tensioning roller, and means for controlling the current in said electrically energized means.

3. In a tension control system, in combination, a movable tensioning roller, fluid-pressure operated means for actuating said roller, means for regulating the amount of fluid pressure on said fluid-pressure operated means, electrically energized means for governing the operation of said regulating means to control the operation of the tensioning roller, and manually operable means for controlling the current in said electrically energized means.

4. In a tension control system, in combination, a movable tensioning roller, fluid-pressure operated means for actuating said roller, means for regulating the amount of fluid pressure on said fluid-pressure operated means, a solenoid magnet for governing the operation of said regulating means, means for energizing said solenoid magnet, and means for controlling the energization of said solenoid to control the operation of said tensioning roller.

5. In a system for controlling the tension on a strip of material, in combination, an idler roller, a lever mechanism for forcing said roller against the material, fluid-pressure operated means for actuating said lever mechanism, means for regulating the amount of fluid pressure on said fluid-pressure operated means, and electrically energized means for governing the operation of said regulating means to control the tension on said material.

6. In a system for controlling the tension on a strip of material, in combination, an idler roller, a lever mechanism for forcing said roller against the material, fluid-pressure operated means for actuating said lever mechanism, means for regulating the amount of fluid pressure on said fluid-pressure operated means, electrically energized means for governing the operation of said regulating means to control the tension on said material, and means for controlling the current in said electrically energized means.

7. In a system for controlling the tension on a strip of material, in combination, a bell-crank lever, an idler roller mounted on one end of said lever, a fluid-pressure operated piston disposed at the other end of said lever to force said roller against the material, a pressure regulating valve for regulating the amount of fluid pressure on said piston, electrically energized means for adjusting said regulating valve, and means for controlling the energization of said electrically energized means to change the pressure on said piston, thereby controlling the tension on said material.

8. In a system for maintaining a predetermined tension on a length of material extending between a plurality of roll stands, comprising means for controlling the speed of the rolls of one of the roll stands, pressure fluid actuated means operable to subject the material between the roll stands to a transverse force to deflect the material from its normal pass line between the roll stands and thus subject the material to tension, said pressure fluid actuated means being so constructed and disposed as to automatically vary the transverse force in accordance with its operating position between predetermined limits to subject the material to a substantially constant tension, and means responsive to the operation of the tensioning means for controlling the operation of the speed controlling means, thereby to maintain such relative speeds of the roll stands as will hold the tensioning device within its predetermined operating limits.

9. In combination, a plurality of spaced work devices for simultaneously working a piece of material extending therebetween, a motor for actuating each work device, self compensating pressure fluid actuated means for exerting a transverse thrust upon the material so constructed and disposed as to subject said material to a substantially constant tension and deflect it from its normal pass line between the work devices, and means including a voltage regulator responsive to the movements of said thrust exerting means for controlling the excitation of at least one of said motors, thereby to maintain a substantially constant length and deflection of the material between the work devices. 15

10. In combination, a plurality of spaced work devices disposed to simultaneously work a piece of material extending therebetween, a pressure fluid actuated device positioned between the work devices disposed to subject the material to a transverse thrust to deflect the material from its normal path of travel and thus tension the material, said device being so constructed and disposed as to be self-compensating thereby to subject the strip to predetermined tensions over a predetermined range of movement, and regulator means controlled in accordance with the position of the pressure fluid actuated device within said predetermined range of movement for controlling the speed of at least one of said work devices, whereby the length of material and degree of deflection thereof between the work devices is controlled to maintain the pressure fluid actuated device in a predetermined position.

11. In combination, a plurality of spaced roll stands for simultaneously rolling a piece of material extending therethrough, means for driving the roll stands, means including a pressure fluid actuated roller positioned intermediate the roll stands for subjecting the material to a transverse force to thereby tension it, said means being so constructed and disposed as to so vary the transverse force as to subject the material to a substantially constant tension over a predetermined range of movement of the roller and angular displacement of the material from its normal path of travel by said roller, means for varying the speed of one of the means for driving the roll stands, and a regulator controlled in accordance with the position of the pressure fluid actuated roller within said predetermined range of movement for controlling the speed varying means, whereby the length of material extending between said roll stands and the degree of deflection thereof are so controlled as to maintain said roller within the predetermined range of movement. 55

12. In combination, a plurality of work devices arranged in spaced relation for simultaneously working a piece of material extending therebetween, means for driving each work device, a pressure fluid actuated pressure roller disposed between the work devices for exerting a transverse deflecting force upon the material to tension the material and cause it to move in an angular path with respect to its normal path of travel, said pressure roller having a predetermined operating range and being so constructed and disposed as to automatically function within said predetermined operating range to vary the force exerted upon the material in proportion to its degree of angular deflection, and means controlled by said pressure fluid actuated pressure roller for controlling the speed of at least one of the driving means to control the length of 75

the material between roll stands and consequently the degree of angular deflection to maintain the pressure fluid-actuated pressure roller within its predetermined operating range.

13. In combination with metal working devices adapted for simultaneous operation on a strip of material passing therethrough under tension, of tensioning means positioned intermediate the work devices for subjecting the material to a transverse force deflecting the material out of its normal straight-line path of travel, said means comprising a pivotally mounted pressure fluid

actuated bell crank lever device having a pressure roller disposed to engage the material mounted on one arm thereof, the arms of the bell crank being so disposed in such a predetermined angular relationship as to cause the transverse deflecting force exerted by the pressure roller to be automatically varied in accordance with the degree of deflection of the strip to maintain a substantially constant tension thereon throughout a predetermined range of deflection. 10

GERHARD P. LESSMANN.
